HORACE C. KELLEY, OF EAST CLEVELAND, OHIO.

BUILDING-BLOCK.

948,752.

Specification of Letters Patent. Patented Feb. 8, 1910.

Application filed September 8, 1908. Serial No. 451,946.

To all whom it may concern:

Be it known that I, SHERBURNE H. WIGHTMAN, a citizen of the United States, residing at Cleveland, in the county of Cuyahoga and State of Ohio, have invented a certain new and useful Improvement in Building-Blocks, of which the following is a full, clear, and exact description, reference being had to the accompanying drawings.

10 This invention relates to building blocks, and it has for its object the production of a block of that character which shall be absolutely waterproof on those parts which are exposed to the elements, which shall be 15 capable of use in a manner to produce varied architectural effects, which shall have embedded in its exposed surface waterproof plates, such as tile, which may be arranged according to any desired pattern, and which 20 shall have special means for securely anchoring said plates into the block at the rear thereof.

The above and other objects will be more fully set forth in the description of the 25 structure shown in the accompanying drawings, in which—

Figure 1 is a perspective view showing one of my improved building blocks having one of its faces provided with waterproof face plate, said face plates being arranged in that style of architecture known as the Flemish bond and having its ends provided with projections in order that the blocks may carry out the same style bond interlocked at their ends; Fig. 2 is a perspective view of one of the blocks showing the face plates and the sheet of perforated waterproof material for spacing the plates and also showing the metal anchor bars secured 40 to the backs of said plates by means of which the plates are securely anchored to the block; Fig. 3 is a section taken transversely through the block on the plane 3—3 of Fig. 1; Fig. 4 is a sectional view taken through 45 one corner of the block on a plane at right angles to the plane of Fig. 3; Fig. 5 is a view in perspective of one of the metal anchor bars; Fig. 6 is a perspective view showing my invention applied to a corner block; Fig. 7 shows a special form of face plate for use on corner blocks for buildings, 50 porch columns, chimneys, etc.; Fig. 8 shows a modified form of corner block in which the usual form of face plate is employed, the 55 joint at the corners being covered by a

special form of plate; and Fig. 9 is a perspective view of the corner face plate shown in Fig. 8.

Building blocks are as a rule, formed of monolithic concrete, the block being substantially homogeneous throughout. These blocks are not waterproof, but on the other hand, they have the capacity of absorbing considerable quantities of water so that, when they are exposed to the elements, they not 65 only become water soaked,—thus forming a cold and damp building,—but the material of which the blocks are formed becomes discolored so that, in a comparatively short time, buildings formed thereof present 70 an unattractive appearance. These blocks have been found to be suited admirably for interior work, but for the reasons above stated, they have not proven satisfactory for outside construction. 75

To overcome the above stated objections, I so form the outside or exposed portions of my blocks as to render them impervious to water. I accomplish this object by molding the body of the block about rearwardly 80 projecting members on terra cotta or other suitably formed face plates, and by placing in the spaces between said plates a waterproof sheet, which may be, and at present preferably will be, formed of thick paper. 85 The rear sides of the face plates will preferably be rabbeted to receive the said sheet and thus form a closely fitting joint therewith. In order to securely hold the face plates to the main body of the block, I attach to the plates metal anchor bars which have their ends engaging with lugs extending from the rear sides of the block, the bars being bowed outwardly so as to become thoroughly embedded in the cementitious 90 material forming the body of the block. The exposed face of the block is therefore formed of the waterproof face plates, and the joints between said face plates are so obstructed by the water proof sheet that the 100 entire exposed face of the block is rendered waterproof.

The blocks may be formed of any desired size or shape, the invention being admirably adapted for forming blocks for corners of 105 buildings, for porch columns, for chimneys, etc. They may also be formed of the necessary length for spanning the openings formed in the walls for doors, windows, etc., in which case, they may be suitably rein- 110

forced by metal bars if found desirable, the face plates being arranged on the exposed faces of these blocks to conform to the bonding pattern employed in the blocks forming 5 the main parts of the wall. The sills, the coping, caps, etc., used in the building may also be formed with waterproof face plates.

Taking up a more detailed description by the use of reference characters, 1 represents 10 one of the blocks that is constructed in accordance with my invention, said block being cored out so as to form air spaces 2 within the body thereof, as many of such air spaces being employed as may be deemed 15 desirable; Fig. 1 of the drawing showing two of such spaces that are separated by a partition 3. The face of said block that is to be exposed in the building is composed of face plates, said plates being represented 20 by the reference characters 4 and 4^a, the former of which are longer than the other face plates and are usually termed "stretchers", while the face plates 4^a are called "headers". Of course any size, shape and 25 arrangement of face plates may be employed, but I have chosen to show the form illustrated in Fig. 1, in which these stretchers and headers are arranged in the order known as the Flemish bond. At each of 30 the ends of the block the stretchers 4 extend beyond the adjacent headers so as to provide projecting portions 5 with spaces between the same into which corresponding projections on the next adjacent block may 35 extend, thus locking the blocks together into a solid wall. In assembling these blocks into a wall, the end joints will be staggered so that the partitions 3 between the air spaces will not lie in the same plane, but 40 will be substantially between the end joints of the adjacent tiers of blocks. It is desirable to have as free circulation of air within the walls of the building as is practicable, and, for this reason, the ends of the 45 partition 3 are scalloped or notched at 6, thus leaving air spaces throughout the wall of the building. For the purpose of more thoroughly bonding the tiers of the blocks together and thus strengthening the walls, 50 the sides of the blocks that are to abut in the wall are provided with grooves 7, the grooves in one block registering with the grooves in the adjacent tiers of blocks so as to form a channel between the blocks, into 55 which the mortar that is placed between the blocks in the building will extend so as to form a key and thereby securely lock the blocks together, so there can be no relative movement between them.

60 The face plates 4 and 4^a comprise an outer flat face portion, and inwardly extending ribs 8, which ribs preferably extend transversely across the rear face of the plate; and, for the purpose of affording a more secure anchorage in the block, the ribs are preferably 65

dove-tailed, as shown, so as to be wider at their outer parts than they are adjacent the main body of the plate. While the drawings show these ribs as extending entirely across the plate, they may be made shorter if preferred. The dove-tail shape given to these ribs is ordinarily sufficient to securely anchor the plates to the block; but, in order to avoid any possibility of the plates breaking loose from the blocks, I prefer to anchor the 70 same by means of metallic anchor-bars 9 and 9^a, one of which is shown in detail in Fig. 4, the bars 9 being employed on the stretcher plates and the bars 9^a on the header plates. These bars are curved, as shown, so as to cause the same to project some distance from the rear faces of the face plates and become deeply embedded in the cementitious material forming the main body of the block. The anchor bars are preferably round in section 75 with their ends flattened at 10, which ends are adapted to be projected beneath the dove-tailed sides of the lugs 8. By flattening the bars in this manner they are not so liable to turn on the blocks. The bars may 80 be squared, or flattened throughout, if desired. As shown in Fig. 2, the edges of the ribs 8 are preferably provided with semi-circular notches 11 with which the bars engage above their flattened portions, and the 85 plates are also preferably recessed at 12 so that the ends of the bars may become more deeply and firmly anchored or attached to the plates. If desired, the ribs may be omitted and the ends of the bars cemented in the 90 recesses in the rear faces of the plates.

As is well known, concrete or cement is much stronger in compression than it is in shear or tension. Owing to its comparative weakness in shear, the cement of the block which projects beneath the dove-tailed edges of the lugs 8 is likely to become broken, thus 95 releasing the block. With the bars 9 and 9^a curved in the form shown, it will be seen that the face plates cannot be removed from the cementitious body of the blocks without actually forcing the ends of the bars toward each other; and, as this movement of the ends of the bars would necessitate the application of a force sufficient to compress the 100 concrete, it will be seen that it is impossible to remove the face plates without actually 105 destroying the same. The anchor bars thus serve not only to securely attach the face plates to the body of the block, but they also serve to reinforce the block itself by extending therethrough, and they further serve to 110 equalize the temperatures between the face plates and the block at the rear thereof. As 115 will be understood, the face plates are exposed in the building, and the heat of the sun or the chilliness of the air will heat or chill the face plates to a greater degree than the body of the block which is protected thereby. The face plates and the block will, 120 125 130

therefore, expand and contract differently, and it is desirable to minimize this difference to the greatest possible extent. The ends of the anchor bars, extending into the face 5 plates adjacent their exposed faces, will have substantially the same temperature of the face plates and this temperature will be conducted by the bars into the mass of the concrete at the rear of the face plates, and thus 10 distribute the heat or the cold of the face plates through the block adjacent the anchor bars.

The outer and inner edges of the face plates 4 and 4^a are preferably provided with 15 a groove or rabbet 13 extending entirely about the same. In forming the block, the face plates are laid upon a flat surface, and a sheet of waterproof material 14 is laid over the blocks, the said sheet being perforated at 15 and 15^a so as to permit the rear faces of the plates to project through the sheet, the sheet lying within the rabbeted grooves 13 of the blocks, as shown in Fig. 2. The greater part of the sheet is 20 thus cut away, leaving the same as a sort of grid, the bars of which extend between the plates and close the bottoms of the spaces therebetween. This waterproof sheet and the face plates therefore serve not only 25 to completely waterproof the exposed face of the block, and to prevent the elements in the rear part of the block from combining chemically with the elements in the clay of the face plates, which combination would 30 probably result in the formation of a white coat on the face-plates, as is common in brick work, but the sheet serves as a pattern for spacing the face plates. As this sheet may be perforated according to any 35 desired pattern or system, and the arrangement of the face plates will conform to this system of perforations, it will be seen that any desired arrangement of face plates is 40 easily and accurately secured. The waterproof sheet being thus placed in proper position with respect to the face plates, and the anchor bars 9 and 9^a being in place, the cementitious material forming the body of 45 the block is deposited on the plates and is 50 tamped or pressed into position, as is customary in the formation of building blocks, the anchor bars thus becoming firmly embedded in the block, securely holding the face plates in position. In order to secure 55 still further anchorage, the rear face of the sheet 14 is preferably sanded, as indicated in Fig. 2 by the stipple work thereon. While, as stated, the sheet 14 may be formed 60 of any suitable material, it is my preference at present to form the same of paper similar to tarred roofing paper, such material having the desired water-proofing characteristic, and also having the further characteristic of somewhat softening under the heat of 65 the sun when the blocks are exposed thereto

in the building. This softening quality of the paper causes the same to still further adhere to the face plates and to the block and to thus close all pores therein so as to render the entrance of moisture impossible. 70 The face plates may be spaced apart any desired distance, or their adjacent edges may actually abut, the strips between the perforations in the sheet 14 being correspondingly narrow and resting, as described, 75 in the grooves or rabbets 13.

As shown particularly in Figs. 2 and 4, the sheet 14 projects from the body of the block a slight distance, which distance is equal to half of the width of the mortar joint between two adjacent blocks after 80 they are assembled. In assembling the blocks, therefore, the same are placed with the edges of the sheets 14 therein abutting, said abutting edges, owing to the softening 85 tendency in the material of the sheet hereinbefore referred to, tending to adhere together, thus forming a practically continuous waterproof sheet at the joints of the blocks. 90

In the drawings, I have elected to show the outer sides and ends of the face plates tapering or dove-tailed, in which case a dove-tailed space or joint 16 is formed between the face plates, which space may be 95 filled with waterproof cement, as indicated in the drawings. This cement is preferably applied after the blocks are set up in the building, in which case it is impossible to 100 distinguish one block from another, the joints between the blocks being substantially of the same width as the joints between the face plates, so that, assuming the face plates are made to represent bricks, a wall thus formed has the identical appearance of a 105 brick wall. In some cases, however, it is desirable to leave the joints open or to have what is termed a "raked-out joint". When such a joint is desired, I prefer to form the edges of the plates square so as to leave a 110 rectangular channel for the joints. This sort of joint is therefore left open in the building; and the sheet 14 appears at the bottom thereof. This sheet may, in such cases, be colored as desired so as to simulate 115 different colors of mortar, which colors may be painted or otherwise placed on the said sheet either before or after the blocks are formed, or after the blocks are assembled in the building. 120

As a further advantage of my invention, I may mention the fact that, in the building of brick walls, it is necessary to attach the front face of the wall,—which is usually formed of one kind of brick,—to the rear 125 body of the same wall, which rear body is usually formed of an inferior quality of brick. These portions of the wall are usually attached together by the mortar used in the wall, and also by employing whole 130

bricks for headers, which bricks extend rearwardly into the back portions of the wall. In my construction, the front face of the wall is formed of the face plates which are securely embedded in the cementitious material of the block, and no inwardly extending headers are required.

In Fig. 6, I have shown a block for use on the corners of buildings, on porch columns, chimneys, or any other place about a building where it becomes necessary to carry a wall about a corner. This block preferably has the air spaces 2^a, which are separated by the partition 3^a, and it is also provided with the face grooves 7^a for keying or locking the blocks together. On the faces of this block that are to be exposed I employ face plates 4^b, the same being identical in construction with the face plates 4 and 4^a, except that in Fig. 6 I have shown the face plates arranged according to the American bond system so that the face plates become substantially of the same dimensions. I have elected to show this bonding system in this figure merely for the purpose of illustrating the applicability of my invention to different architectural arrangements of the face plates. This corner block is also shown with regular ends rather than with the staggered ends, shown in Fig. 1, this regular end construction being also illustrated for the purpose of showing the adaptability of my invention to different forms of blocks. At the corners of the block I employ corner face plates 4^c, the same being shown in perspective in Fig. 7, from which it will be seen that one side or leg of the block is of substantially twice the length of the other, the long leg of one face plate alternating with the shorter leg in the next adjacent course of face plates on the block, as shown in Fig. 6. On the rear faces of the plates 4^c, I form the groove or rabbet 13^a for receiving the waterproof sheet. These corner blocks are also provided with the dovetailed ribs 8^a, the same corresponding in construction with the ribs 8 hereinbefore described. The metallic anchor bars are preferably placed diagonally across the corners so as to project into the cementitious material of the block at the rear of the corners. As shown in Fig. 7, the longer leg of the face plate is provided with a pair of ribs 8^a, while the shorter leg has but a single one of such ribs, and the anchor bar 9^b is extended from the outer rib of the longer leg to the rib on the shorter leg. This construction is preferred for the reason that a longer bar may be employed, which can secure a firmer anchorage in the cement than would be the case if a short bar were used between the lug on the shorter leg and the adjacent lug on the longer leg of the plate.

In Fig. 8 I have shown a modified construction for the corner of a block, in which

face plates 4^d are employed upon the sides, a mortar space or joint being left between the adjacent edges of the face plates at the corner of the block. These blocks have the ribs 8^d of the same construction as the ribs 8 and 8^a, hereinbefore described, and also the rabbeted groove around the outer edge of the rear side of the face plates for the waterproof sheet 14^a, said sheet closing the inner part of the joint between the face plates 4^d. In order to hide the joint between the face plates at the corner of the block, I employ a waterproof curved plate or molding 4^e, the edges of which rest against the outer faces of the face plates near their adjacent ends, the curved plate forming what may be termed a waterproof molding covering the corner of the block. This molding is shown in perspective in Fig. 9, from which it may be seen that the ends of the molding are partially closed by projections 4^f, said projections having on their adjacent faces depressions 4^g into which extend the ends of an anchor bar 9^a. This anchor bar extends rearwardly through the joint between the face plates 4^d into the cementitious material of the block at the rear of the face plates, thus firmly anchoring the molding 4^e to the main body of the block and holding the same securely against the outer faces of the face plates. In order to retain the ends of the anchor bar 4^a in the recesses 4^g, the interior space 4^h of the molding is filled with cementitious material, the same being preferably waterproof cement, said material also extending into and filling the joint between the face plates at the corner of the block.

A building constructed of blocks made in accordance with Fig. 8 presents a unique and attractive appearance owing to the molding which protects and conceals the more or less ragged and unsightly corners of the building.

While I have shown the embodiment of my invention as at present I prefer to use the same, I desire it to be understood that the following claims are not intended to be limited to the details of construction shown, any further than is rendered necessary by the specific terms therein employed.

I claim:

1. A building block for exterior wall construction, said block having a main body portion formed of cementitious material and adapted to support the weight of the super-added structure, a plurality of water proof face plates attached to one of the faces of the block that is exposed in the wall, metallic anchors engaging the face plates and embedding in the body portion of the wall, and a layer of water proof material separating the cementitious material from the face plates at the rear edges of the latter to prevent the entrance of moisture into the body.

- of the block, the metallic anchors holding the face plates to the block.
2. In a building block for exterior wall construction, the combination with the main body portion of the block, said body portion being formed of cementitious material, of a plurality of face plates formed of waterproof material, means for attaching the face plates to the cementitious material of the body of the block, and a sheet of waterproof material surrounding the rear edges of the face plates for preventing the entrance of moisture about the plates.
3. In a building block, the combination with a face plate formed of waterproof material, of cementitious material forming the body of the block, means for attaching the face plate to the cementitious material, and a sheet of waterproof material surrounding the rear edges of the face plate for preventing the entrance of moisture about the plate.
4. In a building block, a perforated sheet of waterproof material, the perforations in which sheet are arranged according to a pre-arranged order, a plurality of face plates of waterproof material having their rear sides projecting through the said perforations in the sheet, cementitious material forming the body of the block at the rear of the face plates and at the rear of the said sheet, and means for attaching the face plates to said cementitious material, whereby the face plates and the said sheet form a continuous waterproof face for the block.
5. In a building block, a perforated sheet of waterproof material, the perforations in which are arranged in definite order, a plurality of face plates, one for each perforation in the sheet and having their rear faces extending into the said perforations, the portions of the sheet between the perforations bridging across the spaces between the face plates, cementitious material at the rear of the face plates and at the rear of the said sheet, and means for anchoring the face plates to the cementitious material, the construction being such that the face plates and the perforated sheet form a complete waterproof face for the block.
6. In a building block, the combination with a face plate of waterproof material, an anchor bar having its ends attached to the rear side of the face plate, and cementitious material forming the body of the block and embedding the said anchor bar therein, whereby the face plate is securely anchored to the body of the block.
7. In a building block, a face plate having lugs on its rear side, the adjacent faces of the lugs overhanging the plate at the bases of the lugs, an anchor bar having its ends engaging beneath the overhanging portions of the said lugs, and cementitious material at the rear of the face plate and embedding the anchor bar, whereby the face plate is securely attached to the body of the block.
8. In a building block, a face plate formed of waterproof material, said plate having lugs on its rear face, the adjacent faces of the lugs being inclined from the body of the plate toward each other so that the outer parts of the lugs overhang the rear face of the plate, a bowed metal bar having its ends projected beneath the overhanging sides of the lugs and spanning the space between the lugs, and cementitious material forming the body of the block and embedding the metal bar therein, whereby the face plate is securely anchored to the body of the block.
9. In a concrete block, a face plate having upon its rear face a pair of projections, the adjacent faces of said projections inclining toward each other and overhanging the rear face of the plate, a metal bar having its ends flattened and bowing outwardly over the face plate between the said lugs, and cementitious material forming the body of the block and embedding the said bar and the projections, whereby the face plate is securely anchored to the body of the block.
10. In a building block, a face plate having on its rear side a pair of projections, the adjacent faces of said projections being inclined toward each other and overhanging the rear of the plate at the base of the projections, said plates also having recesses at the base of the said projections, a bowed anchor bar having its ends projecting into the said recesses and under the overhanging faces of the projections, and cementitious material deposited upon said plate and embedding the said lugs and bar, whereby the face plate is securely anchored to the body of the block.
11. In a building block, the combination with a perforated sheet of waterproof material, of a plurality of face plates having their rear faces extending into the perforations of the said sheet, metallic anchor bars secured at their ends to the rear faces of the said plates, and cementitious material forming the body of the block and covering the rear faces of the face plates and the waterproof material, said cementitious material embedding the anchor bars and securely attaching the face plates and the waterproof sheet to the block.
12. In a building block, a sheet of waterproof material having rectangularly shaped perforations therein arranged in order, a waterproof face plate for each of the perforations in the sheet, each block having its rear face extending into a corresponding perforation in the sheet, and each block having a pair of lugs on its rear face projecting beyond the rear side of the sheet, the adjacent faces of the lugs inclining toward each other so as to overhang the face plate at the rear of the block.

- base of the projections, a bowed anchor bar having its ends extending beneath the overhanging faces of the said projections, and cementitious material deposited upon the rear faces of the plates and sheet and embedding the said projections and anchor bars, whereby the face plates and the sheet are securely anchored to the body of the block and form a waterproof face therefor.
13. In a building block, a sheet of waterproof material having rectangularly shaped perforations therein, a plurality of face plates having their rear faces extending into the said openings, the portions of the sheet between the openings corresponding to the joints between the face plates and closing said joints at the rear, said sheet projecting beyond the block so as to abut with a corresponding projecting sheet in the next adjacent block, cementitious material forming the body of the block deposited upon the rear of the face plates and upon the sheet, and means for securely anchoring the face plates to the said cementitious material.
14. In a building block, a sheet of waterproof material, said sheet having rectangular openings formed therein and arranged in definite order, a face plate of waterproof material for each of said openings, each of said face plates having a groove or rabbet formed about the edge of its rear face, that part of the face plate within the said groove or rabbet fitting a corresponding opening in the waterproof sheet, the face plates being projected through said sheet with the latter fitting in the grooves or rabbets, projections on the rear faces of each of said face plates, bowed metallic anchor bars engaging at their ends with the said projections and extending outwardly at their centers from the rear faces of the plates, and cementitious material deposited upon the rear faces of the face plates and upon the water proof sheet, said material embedding the said lugs and anchor bars and securely attaching the face plates and the sheet to the body of the block.
15. A building block having attached to one of its faces a plurality of spaced face plates of water proof material, cementitious material forming the body of the block to which the plates are attached, water proof material differing from the cementitious material at the rear of the edges of the face plates for preventing the entrance of moisture into the block, the spaces between the face plates being open whereby raked out joints are provided.
16. A building block for exterior wall construction, said block having a main body portion formed of cementitious material and adapted to support the weight of the super-added structure, a plurality of water proof face plates attached to one of the faces of the block that is exposed in the wall, lugs on the rear faces of said face plates, and metallic anchor bars engaging at their ends with said lugs and extending inwardly therefrom and embedding in the cementitious material of the body of the block, the spaces between the face plates being left open whereby raked out joints are provided between the face plates.
17. In a building block, a plurality of waterproof face plates arranged in definite order and spaced at their edges so as to form joints between the plates, anchor bars attached to the rear faces of said plates and bowing outwardly therefrom, waterproof paper resting upon the rear faces of the plates at their edges and spanning the spaces between the plates, and cementitious material deposited upon the rear of the plates and the paper and embedding the anchor bars therein.
18. In a building block, a perforated sheet of water proof material having its rear face sanded, the perforations in which sheet are arranged according to a prearranged order, a plurality of face plates of water proof material having their rear sides projecting through the said perforation in the sheet, cementitious material forming the body of the block at the rear of the face plates and at the rear of the said sheet, said material adhering to the sanded face of the said sheet, and means for attaching the face plates to said cementitious material, whereby the face plates and the said sheet form a continuous water proof face for the block.
19. In a building block, a perforated sheet of water proof material having its rear face sanded, the perforations in which sheet are arranged in definite order, a plurality of face plates, one for each perforation in the sheet and having their rear faces extending into the said perforations, the portions of the sheet between the perforations bridging across the spaces between the face plates, cementitious material at the rear of the face plates and at the rear of the said sheet, the said material adhering to the sanded surface of the sheet, and means for anchoring the face plates to the cementitious material, the perforated sheet preventing the entrance of the cementitious material between the edges of the face plates and thus providing open or raked out joints.
20. In a building block, a plurality of waterproof face plates arranged in definite order and spaced at their edges so as to form joints between the face plates, a sheet of paper having openings therein corresponding in position with the desired location on the block of the face plates, said paper being treated with material that will soften under the heat of the sun, the rear faces of the plates projecting through said opening and the paper bridging across the spaces between

the plates, and cementitious material forming the body of the block deposited on the rear faces of the face plates and paper.

21. A building block having attached to one of its faces a plurality of spaced face plates of waterproof material, said plates having their rear edges beveled so as to form dove-tailed joints between the plates, cementitious material forming the body of the block to which the plates are attached, and means for preventing the cementitious material from entering between the plates, whereby an open or raked-out joint is provided.

22. In a building block, the combination of a plurality of spaced face plates having projections on their rear faces, said face plates being formed of waterproof material and having their rear edges beveled, cementitious material forming the body of the block and embedding the said projections on the face plates for attaching the latter to the block, and a waterproof sheet for preventing the entrance of the cementitious material between the face plates, whereby an open or raked-out dove-tailed space is provided between the plates.

23. In a building block, a perforated sheet of waterproof material, the perforations in which sheet are arranged in definite order, a plurality of face plates of waterproof material, having their rear edges beveled and having their rear sides projecting through the said perforations in the sheet, cementitious material forming the body of the block at the rear of the face plates and at the rear of the said sheet, and means for fastening the face plates to said cementitious material, whereby the face plates and the cementitious material form a complete waterproof face for the block, and the said sheet prevents the cementitious material from entering the spaces between the face plates, thus providing open dove-tailed spaces between the face plates.

24. In a building block, the combination

with a perforated sheet of water proof material, of a plurality of face plates having their rear faces extending into the perforations of the said sheet, projections on the rear sides of the face plates, the adjacent faces of said projections on each block being inclined toward each other and overhanging the rear of the plates at the bases of the projections, a bowed anchor bar for each face plate, said bar having its ends projecting under the overhanging faces of the projections on the plate, and cementitious material forming the body of the block and, embedding the said lugs and anchor bars, whereby the face plates and the perforated sheet are securely anchored to the body of the block.

25. A building block having attached to one of its faces a plurality of spaced face plates of water proof material, cementitious material forming the body of the block to which the plates are attached, and water proof material differing from the cementitious material between the edges of the face plates for preventing the entrance of moisture into the block.

26. A building block having attached to one of its faces a plurality of spaced face plates of water proof material, said plates being arranged according to a definite order, cementitious material forming the body of the block to which the plates are attached, and water proof material differing from the cementitious material between the face plates for preventing the entrance of moisture into the block, the face plates and the ends of the blocks being staggered so that the blocks may securely lock together at their ends.

In testimony whereof, I hereunto affix my signature in the presence of two witnesses.

SHERBURNE H. WIGHTMAN.

Witnesses:

S. E. FOUTS,
A. J. HUDSON.
